HENRY G. SCHLESINGER, OF NEW YORK, AND LLOYD FOMHOF, OF BROOKLYN, NEW YORK

PELT PRINTING MACHINE

Application filed August 9, 1929. Serial No. 384,713.

This invention relates to a pelt printing machine, that is, a machine for printing, stamping, or otherwise impressing a legend of any character on the hide or skin side of pelts. It will be understood, however, that while the machine made in accordance with our invention is particularly adapted for this purpose it is not specifically so limited, and also that the legend printed, stamped or impressed on the pelts may be a name, symbol, or other designation, as, for example, the name of the manufacturer, or seller, or a trade mark, or a trade name, or otherwise.

The object of the invention is the provision of a machine for printing, stamping or impressing a legend, or other designation, on pelts and in carrying out the same the apparatus includes an endless conveyor moved intermittently to successively bring sections thereof over a yielding support, together with means for imparting an intermittent movement to the conveyor, a platen and inking table, or other similar printing apparatus, with means for actuating the same to move the platen into contact with the inking table during the travel of the conveyor and into contact with a pelt during an interval when the conveyor is stationary, there being also provided a common means for actuating the several parts of the apparatus, all of which will be hereinafter more particularly described.

In the drawings Figure 1 is a side elevation of a machine made in accordance with this invention,

Fig. 2 is a plan of the same,

Fig. 3 is an end elevation thereof,

Fig. 4 is a sectional elevation taken on line 4—4, Fig. 1,

Fig. 5 is an enlarged section on line 5—5, Fig. 1,

Fig. 6 is a plan on an enlarged scale taken on line 6—6, Fig. 1,

Fig. 7 is a section on line 7—7, Fig. 1, also on an enlarged scale,

Fig. 8 is a sectional perspective showing a section of the conveyor belt, and

Fig. 9 is a section on line 9—9, Fig. 2.

By reference to the drawings it will be seen that the apparatus to which the invention re-

lates may be embodied in a machine having a frame composed of posts 10 and 11 at one end and posts 12 and 13 at the other end, which as illustrated may be made of channel irons. These posts are connected by top longitudinal rails 14 and 15 and lower longitudinal rails 16 and 17, together with end rails 18 and 19, these parts being suitably connected and braced as may be required. The frame also includes a lateral extension which may be composed of upright posts 20 and 21 and side rails 22 and 23. This extension of the frame may be placed at one side thereof at any suitable or convenient position.

Mounted in the lower part of the extension of the frame there is a motor 24. This, as illustrated, may be placed on blocks 25 secured in the frame extension. A pulley 26 is mounted on the motor shaft 27 and a belt 28 passes over the pulley 26 and also over a pulley 29 mounted on a counter shaft 30 which is journaled in suitable bearings 31 and 32 fixed in the frame of the machine. On the counter shaft 30 there is a sprocket 33. A chain 34 passes over this sprocket 33 and also over a sprocket 35 mounted on a shaft 36. The shaft 36 is journaled in suitable bearings 37 and 38 which are also carried by the frame of the machine.

On one end of the shaft 36 there is a sprocket 39, the use of which will be hereinafter described, while at the opposite end of this shaft 36 there is a gear, preferably a beveled gear 40. This beveled gear 40 meshes with a beveled gear 41 mounted on a shaft 42 journaled in the bearings 43 and 44, which are also connected to and carried by the frame of the machine. On the end of the shaft 42 opposite to that on which the beveled gear 41 is connected there is a crank arm 45.

Suitably mounted in the frame of the machine and running longitudinally thereof in spaced positions there are rods 46 and 47. On the rod 46 there is a sliding sleeve 48 and similarly on the rod 47 there is a sliding sleeve 49. Depending from the sleeve 48 there is an arm 50 and in a similar manner depending from the sleeve 49 there is a corresponding arm 51. The lower ends of these arms are connected by a rod 52. Mounted at

one end to swing on the rod 52 there is a link 53. A similar link 54 is mounted to turn at the free end of the crank 45. A connecting rod 55 carrying threaded extensions 56 and 57 extends between and connects the links 53 and 54 in an adjustable manner whereby, as will be understood, the sleeves 48 and 49 are caused to reciprocate on the rods 46 and 47 through the action of the crank 45, the extent 10 of the travel of the sleeves 48 and 49 depending upon the adjusted length of the connecting rod 55 which is controlled by the screw threaded extensions 56 and 57 thereof. A trip arm 58 is pivotally connected, as indicated at 59, to the sleeve 48 and the lower end of this trip arm is normally maintained in an initial position against a stop 60 by means of a spring 61, or otherwise, which extends between the lower end of the trip arm and a 20 pin, or other connection, for the spring carried by the sleeve. In a similar manner a trip arm 62 is pivotally connected, as indicated at 63, to the sleeve 49. The lower end of the trip arm 62 is adapted to bear against a stop 64 when the trip arm is in its normal 25 position and a spring 65 is employed to normally maintain this trip arm in this position, the spring 65 extending from the lower end of the trip arm to a suitable pin, or other connection therefor, carried by the sleeve 49. The upper ends of these trip arms 58 and 62 extend through slots provided therefor in the upper longitudinal rails 14 and 15 and are adapted to engage parts of an endless 30 conveyor, as hereinafter described, in order to impart an intermittent movement thereto.

The apparatus also contemplates the use of an endless conveyor 66. This is preferably a belt made of canvas or other suitable material. This conveyor belt passes over a pulley 67 mounted on a shaft 68, which is journaled in suitable bearings 69 at one end of the machine, and also passes over a pulley 70 mounted on a shaft 71, which is journaled in bearings 72 carried by the opposite end of the machine. The conveyor belt also passes under an idler pulley 73 journaled in bearings 74 carried by the lower longitudinal rails, as well as under a pulley 75 carried by a shaft 76 which is journaled in bearings which are adjustable to position and also carried by the lower longitudinal rails of the machine.

The bearings in which the shaft 76 is journaled are indicated at 77 and 78. These are similarly constructed and mounted and consequently but one of them will be specifically described. As shown in Figs 6 and 7, for example, the bearing 77 is adapted to slide on a guide 79 provided therefor on the lower longitudinal rail 17 and passing through the bearing 77 there is a screw threaded rod 80. The end portions of the rod 80 are mounted in brackets at 81 and 82 also carried by the lower longitudinal rail 17 whereby, as will be un-

derstood, by turning the screw threaded rod 80 the bearing 77 may be adjusted to position in order to vary the tension on the endless conveyor. Nuts 83 and 84 may be employed to lock the screw threaded rod 80 in position. 70

A brake device may also be employed to retard as far as may be necessary the travel of the conveyor and, as will be understood, to also bring the same to a positive stop and maintain it in position after each movement or shifting thereof. This brake device may include a lever 85 pivotally mounted as indicated at 86 on a bracket 87. At one end of the lever 85 there is a roller 88 adapted to bear against the surface of the pulley 70, whereas the opposite end of the lever 85 is connected by a spring 89 to a turn buckle 90, which in turn is connected to a bracket 91 carried by the machine frame in order to vary the tension in the spring 89 and consequently and correspondingly to vary the tension on the lever 85 and the pressure with which the roller 88 engages the surface of the pulley 70. 90

The endless conveyor, as hereinbefore stated, may be made of canvas, or other similar material, and is preferably so constructed as to be divided into sections. To this end we employ a plurality of bars 92 made of suitable material and extending transversely of the conveyor. Associated with each bar, as clearly shown in Fig. 8, there is a channel member 93. Each channel member 93 fits over its bar 92 with a portion of the conveyor belt intervening and these parts are secured to one another by means of screws indicated at 94, or otherwise. As indicated in Fig. 2 of the drawings each cross bar 92 and its channel member 93 extends appreciably beyond the edges of the endless conveyor at both sides thereof. The cross bars 92 and their channel members 93 divide the conveyor into a plurality of sections and these may be of any desired length depending upon the distance between adjacent cross bars and their channel members. Each of these sections in the conveyor belt is adapted to receive and move a pelt, or other material, upon which a print or other impression is to be made. The projecting ends of the cross bars and their channel members 93, as well as the adjacent edge portions of the conveyor belt, travel in and between and are supported by the longitudinal rails 14 and 15 during that portion of the travel of the parts of the conveyor belt in which it is caused to move horizontally from one to the other end of the apparatus. 110

Passing over the sprocket 39, which as hereinbefore described is carried by the shaft 36, there is a chain 95. This chain 95 also passes around a sprocket 96 mounted on a shaft 97 which is suitably journaled in bear- 120

ings 98 carried by the frame of the machine. On the shaft 97 there is a crank 99. One end of a connecting rod 100 is connected to the crank 99 and the opposite end of this connecting rod is connected to a cross rod 101 extending between and to which there are pivotally connected rocker levers 102 and 103. These rocker levers are carried by a shaft 104 which is journaled in bearings 105 suitably connected to and carried by the frame of the machine. The cross rod 101 extends between the lower ends of the rocker levers 102 and 103 and extending between the upper ends of these rocker levers there is a cross rod 106. Passing at right angles through this cross rod 106 and preferably in a centrally disposed position there is a plunger 107. The downward movement of the plunger 107 is limited by a pin 108 secured 10 in the plunger and adapted to engage the cross bar 106 or otherwise. At its lower end the plunger 107 carries a printing head 109 adapted to contain a form of any desired nature for printing, or stamping, or otherwise marking the articles to be thus treated, and the plunger 107 and the printing head 109 are yieldingly maintained in the position as shown in Fig. 1, for instance, by means of a spring 110 or otherwise. When in this position the printing head and its form are adapted to contact with an inking table 111 suitably supported on brackets 112, or otherwise. In order to maintain the plunger 107 in an upright or vertical position we employ a T-member connected to the cross rod 106, as illustrated in Figs. 1, 2, 3 and 4. The leg 113 of this T-member is connected to the cross bar 106 exteriorly of the rocker lever 103. The cross bar 114 of the T-member has corresponding ends of positioning rods 115 and 116 pivotally connected thereto. The opposite ends of these positioning rods 115 and 116 are pivotally connected in brackets 117 and 118 suitably secured to the frame of the machine whereby, as will be understood, the cross bar of the T-member will always be maintained in a horizontal position irrespective of the position of the rocker levers and consequently inasmuch as the plunger operates in the cross bar 106 at right angles thereto this plunger will always be maintained in an upright or vertical position.

At a suitable station the upper longitudinal rails are fitted with a base 119 extending between and secured in position therein and on this base 119 there is placed a pad 120 of rubber, or other similar and equivalent yielding or resilient material. This base and pad are so placed that when the rocker levers 102 and 103 are moved to the position shown in dotted lines, Fig. 4, the printing head is adapted to contact with a pelt or other article carried by the conveyor so as to yieldingly impress the same but, as will be understood, with sufficient force to adequately transfer from

the form in the printing head an impression on the pelt.

The apparatus may also be constructed to include a table 121 extending between the upper longitudinal rails and overlying the conveyor belt and upon which the pelts 122, or other articles, may be stacked, or otherwise placed preparatory to transferring them to the conveyor. These pelts are manually transferred from the table 121 to the upper 70 horizontally traveling portion of the conveyor belt in such a manner that a pelt is placed on each section of the conveyor belt, that is, between each of the transverse channels 93. The parts of the apparatus, as hereinbefore described, are so geared and timed that the trip arms 58 and 62 are actuated by the movement of the sleeves 48 and 49 from right to left, as viewed in Fig. 1, in order, during this movement of the sleeves, to engage the projecting ends of a channel 93 and to thereby shift the conveyor belt a predetermined distance, depending, of course, upon the length of the connecting rod 55, assuming the length of the crank 45 is fixed. It will be understood, of course, that in the movement of the sleeves 48 and 49 in the opposite direction the trip arms 58 and 62 will be swung against the actions of the springs 61 and 65 so as to permit the upper end of these trip arms to pass under the extending ends of the next succeeding channel 93 and that during the return movement of the sleeves 48 and 49 and the trip arms carried thereby the conveyor belt will remain stationary. As the 100 conveyor belt becomes stationary, or during the interval in which it is stationary, the printing head 109 is moved by the rocker levers 102 and 103 to the position as shown in Fig. 4 as aforesaid to cause the form in the 105 printing head to come into yielding contact with the skin or hide surface of a pelt with sufficient pressure to transfer an impression from the form to the pelt. Obviously the beginning of the return movement of the 110 printing head by swinging the rocker levers in the opposite direction is started before the next succeeding shift in the conveyor belt is effected. It will furthermore be understood that the construction of the machine as herein 115 illustrated and described is more or less diagrammatic and that other and equivalent forms of the various parts of the apparatus may be employed for accomplishing like purposes without departing from the nature and spirit of the invention.

We claim as our invention:

1. In a machine for printing on pelts and the like, a frame, rocker levers, a plunger carried by the rocker levers, a printing head connected to the plunger, means for maintaining the plunger in an upright position during the movement thereof and that of the printing head with the rocker levers, and means for 120

actuating the rocker levers to bring the printing head into a printing position.

2. In a machine for printing on pelts and the like, a frame, rocker levers mounted in the frame, a plunger carried by the rocker levers, a printing head connected to the plunger, an inking table, means for maintaining the plunger in a substantially vertical position during the movement of the said rocker levers, and means for actuating the said rocker levers to bring the said printing head alternately in a printing position and in a position in which it contacts with the said inking table.

15 3. In a machine for printing on pelts and the like, a frame, rocker levers mounted in the frame, a plunger yieldingly mounted in the said rocker levers, a printing head carried by the said plunger, a T-member connected to the rocker levers, positioning rods connected to the said T-member for maintaining the said plunger in a substantially vertical position at all times during the movement of the said rocker levers, an inking table, and 20 means for actuating the rocker levers to alternately move the head and plunger in the position in which the head bears against the inking table and in which the head is in a printing position.

30 4. In a machine for printing on pelts and the like, a frame, an endless conveyor having sections therein for the reception of pelts to be carried thereby, means for imparting an intermittent movement to the said conveyor, 35 rocker levers, a printing head carried by the rocker levers, devices for maintaining the printing head in a predetermined position relatively to the rocker levers during the movement thereof, an inking table, and means 40 for actuating the rocker levers to bring the printing head into position against the inking table during the movement of the conveyor and to bring the printing head into contact with the pelt on the conveyor during 45 an interval between the movements of the said conveyor.

5. In a machine for printing on pelts and the like, a frame, an endless conveyor having sections for pelts to be carried thereby, 50 means for imparting an intermittent movement to the said conveyor, rocker levers, a plunger carried by the rocker levers, a printing head connected to the plunger, means for maintaining the plunger in a substantially 55 vertical position in the movement of the rocker levers, and means for actuating the rocker levers to bring the printing head into position against the inking table during the movement of the conveyor and to bring 60 the printing head into contact with a pelt on the conveyor during an interval between the movements of the said conveyor.

6. In a machine for printing on pelts and the like, a frame, an endless conveyor mounted 65 therein and having sections for the re-

ception of pelts to be carried thereby, means for imparting an intermittent movement to the said endless conveyor, rocker levers mounted on the said frame, a plunger yieldingly mounted on the said rocker levers, a printing head carried by the plunger, a T-member associated with the rocker levers, 70 positioning rods associated with the T-member for maintaining the plunger in a substantially vertical position during the movements of the said rocker levers, an inking table, an impression bed, and means for actuating the rocker levers to bring the printing head in position against the inking table 75 during the travel of the said endless conveyor and into position against a pelt on the conveyor over the impression bed during an interval between the movements of the said endless conveyor.

Signed by us this 2nd day of July, 1929.
